UNITED STATES PATENT OFFICE.

ROBERT C. GRAVES, OF BARNESVILLE, OHIO.

IMPROVEMENT IN VENTILATING APPARATUS FOR RAILROAD-CARS.

Specification forming part of Letters Patent No. 63,880, dated April 16, 1867.

To all whom it may concern:

Be it known that I, ROBERT C. GRAVES, of Barnesville, in the county of Belmont and State of Ohio, have invented a new and useful Improvement in Ventilators for Railroad-Cars and Buildings; and I do hereby declare that the following is a full, clear, and exact description thereof, which will enable others skilled in the art to make and use the same, reference being had to the accompanying drawings forming part of this specification, in which—

Figure 1 is a longitudinal section of my improved ventilating apparatus in a railroad-car. Fig. 2 is an end view of the ventilating-pipe. Fig. 3 is an enlarged partial sectional view of the apparatus. Fig. 4 is a partial bottom view of the ventilating-pipe.

Similar letters of reference indicate like parts.

This invention relates to an improved ventilating apparatus to be applied to railroad-cars, vessels, vehicles, public halls, churches, dwelling-houses, &c.; and consists in a metal or other pipe running through the car, vessel, or building, having funnel-shaped openings on the outside for the admission of fresh air, and provided also with peculiar arrangements for directing the fresh air into a car or room in its passage through the pipe, and for the discharge of foul air.

Fig. 1 represents a railroad-car provided with my improved ventilating apparatus, which illustrates the principle and method of operation thereof in that special application, but may be modified to adapt it to any place or desired position.

A is the body of the car, of which B is the roof. C is a tube of any suitable size and material, which runs lengthwise of the car A on the inside under the roof B, through which both ends are projected. The ends of the pipe above the roof are goose-necked or bent, and turned toward the ends of the car, and are provided with funnel-shaped mouths D D, which are covered with wire-cloth to shut out sparks and cinders or dust, while they will admit fresh air freely. Each end of the pipe is provided with dampers or stop-valves a a, for cutting off the air at either end and regulating the admission and discharge of air, as desired. At some point in or near the middle of

the pipe C a wedge-shaped or double-inclined partition, b, rises from the lower side nearly to the top of the tube on the inside, and on each side of this partition b are a series of crescent-shaped openings or cuts, c c, made in the bottom of the pipe, which are provided with air guides or deflectors d d, placed on the side of each of the openings c c nearest to the middle partition, b, and rising on the inside from the bottom in an inclined position toward the end of the pipe, about half its diameter. These air guides or deflectors d d are thin plates fitted in the pipe on the sides of the openings c c, as shown in Figs. 1, 2. For railroad-cars I also provide supplementary outlets for the foul air by connecting with the pipe C the pipes E E, which pass up vertically through the roof, and are provided with an ordinary ventilating-cowl, e. These pipes E E are placed near the valves a a or over the outermost of the series of openings c c on each side of the middle partition, b, and their lower ends are provided with air-guides or deflecting-plates n, which incline downward toward the middle of the pipe C.

It will be observed that with this arrangement of my ventilating apparatus applied to railroad-cars, the operation will be the same whichever end may go forward, and that the current of fresh air admitted in the front end of the pipe may be regulated perfectly, according to the number of the passengers, the speed of the train, &c., for the purpose of driving out and replacing the foul air produced by the respiration of the passengers, by simply regulating the stop-valves a a; and when applied to buildings the regulation of the ventilating apparatus will be very easy, according to the direction of the wind, the temperature, &c.

The fresh air will enter the bell-mouthed pipe C at the end in front of the car, and the current or volume of air passing into the pipe will be directed by the deflectors d d down through the openings c c into the car, when, by natural laws, the cool fresh air will descend, and the rarefied and foul air will ascend and be forced upward through the openings c c in the opposite end of the pipe, passing upward through the pipe E on that side, or out of the end of the pipe C at the back part of the car, as may be desired. A por-

tion of the fresh air which enters the front end of the pipe will continue its passage and pass over the partition, assisting by its movement in drawing out the rarified and foul air from the inside of the car or room in which the ventilating apparatus may be applied.

Having thus described my invention, what I claim as new, and desire to secure by Letters Patent, is—

The construction and arrangement of the supplementary outlets E E, having deflector

n upon the pipe C, whose ends are curved upward and pass out of the top of the car, and whose under side is provided with crescent-shaped openings e e, having air-guides d d, inclined in opposite directions upon each side of the middle partition, b, as herein set forth, for the purpose specified.

ROBERT C. GRAVES.
